UNITED STATES PATENT OFFICE.

WILLIAM G. CORSON, OF AKRON, OHIO, ASSIGNOR TO THE NATIONAL STANDARD COMPANY, OF NILES, MICHIGAN, A CORPORATION OF MICHIGAN.

SIZING AND SHAPING MACHINE.

Application filed May 20, 1925. Serial No. 31,598.

This invention relates to a sizing and shaping machine and particularly to a sizing and shaping machine for composite tire grommets.

An object of the invention resides in providing a sizing and shaping machine for a composite grommet structure in which suitable sizing and shaping members are movably mounted on a plate member in operative relation for engaging the grommet to be shaped, which are operable by suitable means to effect the fixing and shape of the size of the grommet.

A further object of the invention resides in providing a sizing and shaping machine of the above mentioned character having a plurality of pairs of cooperating shaping elements operable on a plate member by suitable operating means movable in a plane at right angles to the plate member having connection with each of the shaping members of a pair for operating the same in a predetermined manner to effect the sizing and shaping of composite ring structures.

The invention includes other objects and improvements in the details of construction and arrangement of parts which are more particularly pointed out in the following description and claims directed to a preferred form of the invention, it being understood, however, that various changes may be made in the manner of mounting the cooperating fingers for operation on the plate member and the manner of operating the same through the operating means, without departing from the spirit and scope of the invention as herein set forth.

In the drawing forming part of this application,

Fig. 1 is a plan view of the structure forming the subject matter of the invention.

Fig. 2 is a vertical sectional view taken on the line 2-2 of Fig. 1, and

Fig. 3 is a detail perspective view of a ring member clamped in the proper size and shape resulting from the operation of the machine thereon.

A plate member is indicated at 1 which is of annular form having a central opening 2 and a plurality of radial slots 3 opening through the outer periphery of the member. The member throughout the length of these slots and at the side portion thereof is chan-

neled as indicated at 4 for receiving and slidably mounting the inner and outer cooperating fingers 5 and 6, respectively, having guide projections 7 slidably mounted in the channels 4. The plate member is suitably supported in a horizontal position by legs 8 as clearly shown in Figs. 1 and 2. The periphery of the plate member is also formed at predetermined points with recesses 9 which have a purpose to be presently described.

A base plate is indicated at 10 provided with a boss 11 in which is mounted the standard 12 extending upwardly therefrom substantially in axial alinement with the axis of the plate member 1 and provides a slideable mounting for the sleeve 13 of the operating means for the cooperating fingers. This sleeve is limited in its downward movement by a suitable collar 14 adjustably mounted on the standard 12. This sleeve 13 carries upper and lower annular plates 15 which are provided with a plurality of radial recesses in radial alinement with the pairs of sizing and shaping fingers 6 and 7, and cylindrical extensions 15' receiving the locking bolts 15" adapted to adjustably mount the plates on said sleeve 13.

A plurality of operating arms are indicated at 16 which have the inner ends pivotally mounted in the recesses of the upper annular plate 15 while the outer ends are bifurcated as at 17 for receiving the ends of the inner shaping fingers 5 to which they are pivotally secured as indicated at 18. Any length operating arm 16 may be used for producing the desired set of the fingers for the making of rings of a predetermined size. Similar operating arms 19 are pivotally connected in the recesses of the lower collar member while the free ends are bifurcated to receive the lower ends of the shaping members 6 to which they are connected as indicated at 20.

From the above description and with reference to the drawing, it will be understood that in the upward sliding movement of the sleeve 13 on the upright 12 that the operating arms 16 and 19 will be operated to move the shaping fingers 6 and 7 inwardly and outwardly, respectively, so that they will be moved away from each other.

When the fingers are separated as a result of a movement of the parts as above set forth, a composite ring or grommet which it is desired to size and shape may be inserted between the pairs of shaping fingers and upon the downward movement of the sleeve 13 on the upright 12, the members 5 and 6 will be moved toward each other so as to engage the laminations of the ring and 10 through the plurality of radially movable pairs of fingers as illustrated in Fig. 1, it will be seen that the proper size and shape will be transmitted to the composite ring member mounted between the said shaping members. A plurality of suitable forms of clamps 21 are then applied to the ring member 22, which has been properly sized and shaped, and which are accommodated in the recesses 9 of the plate member. These 15 20 25 clamping members are secured tightly upon the laminations of the ring and hold the same in adjustable and shaped relation so that the sizing and shaping members may be moved out of engagement with the ring to permit the removal thereof from the machine for further treatment.

An operating arm 23 is pivotally mounted on the lower side of the plate member intermediate its ends at 24 and is provided with 30 a pin and slot connection 25 at one end with the sleeve 13 while the opposite end forms a handle whereby the sleeve may be manually and readily raised or lowered for operating the fingers. It may also be desirable to allow for freedom of the operator's hands for other uses and, for such convenience, an upright supporting arm 28 is securely positioned upon the base plate 10. Pivotally secured to the arm 28 is a foot operating treadle 29 disposed at right angles to the arm for pivotally supporting the arm 30 which is pivotally connected to the operating arm 23. By pressing the foot upon the treadle the sleeve may be readily raised or lowered for operating the fingers and thus allows the operator's hand freedom for use as may be desired.

Slotted tooth members 26 are adjustably mounted on a plurality of the fingers 6 through the use of the bolts 27 which are adapted to be threaded into one of a plurality of threaded openings in the finger. These tooth members serve to engage the top portion of a ring to be sized and hold the same tightly against the plate member.

From the above description, it will be seen that a substantially simple and novel sizing and shaping structure has been provided for composite ring structures particularly wherein the operating means is adjustably connected to the shaping and sizing fingers and operable so that a movement of the operating means laterally with respect to the plate member will effect the movement of said shaping fingers in a pre-

determined manner. It is to be understood that if desired, the arms 16 and 19 may be made adjustable and any other means for suitably and slidably mounting the shaping fingers on the plate member be provided in lieu of the means illustrated in the drawing without departing from the scope of this invention. 70

What is claimed is:

1. A sizing and shaping machine comprising a plurality of pairs of cooperating sizing and shaping members, means for mounting the members of each pair of cooperating sizing and shaping members for movement toward and away from each other, and single operating means for positively and simultaneously moving the members of each pair toward and away from each other. 75 80

2. A sizing and shaping machine comprising a plurality of pairs of cooperating sizing and shaping fingers, means for mounting the members of each pair for movement toward and away from each other, and operating means for positively and simultaneously moving the members of each pair of fingers toward and away from each other including a link connected with each finger and an operating member connected with all the links. 85 90

3. A sizing and shaping machine comprising an annular table, a plurality of pairs of cooperating sizing and shaping fingers, cooperating means on the fingers and table for constraining the fingers to sliding movement radially of the table, a post fixed centrally of the table, a sleeve slidable on the post, links pivotally connected with the upper end of the sleeve and the inner fingers of the pairs, links pivotally connected to the lower end of the sleeve and to the outer fingers of the pairs, and means for sliding the sleeve on the post. 95 100 105

4. A sizing and shaping machine comprising a table having radial slots, a plurality of pairs of cooperating sizing and shaping fingers slidably fitted in said slots, cooperating means on the table and the fingers for constraining the fingers to sliding movement radially of the table, links pivotally connected with all of the fingers and means pivotally connected with the links and operable to cause the links to move the fingers toward and away from each other. 110 115

5. A machine of the class described comprising a table, a plurality of cooperating sizing and shaping members movably mounted on the table, operating means for said sizing and shaping members for producing a cooperation thereof to size and shape a composite structure in a predetermined manner and means for engaging the top portions of the composite member being shaped to hold the same in contact with the table. 120 125

6. A machine of the class described com- 130

prising a plate member, a plurality of co-operating sizing and shaping members movably mounted on said plate member, operating means for said sizing and shaping members for producing a cooperation there-
5 of to size and shape a composite structure in a predetermined manner, and means ad-

justably mounted on said sizing and shaping members for engaging the top portions of the composite member being shaped to hold 10 the same in contact with the plate member.

In testimony whereof I hereunto affix my signature.

WILLIAM G. CORSON.
